UNITED STATES PATENT OFFICE.

HOWARD C. McDONALD, OF BUFFALO, NEW YORK.

DESIGN FOR A HANGING TOILET-RACK.

47,891.

Specification for Design.

Patented Sept. 28, 1915.

Application filed July 16, 1914. Serial No. 851,407. Term of patent 7 years.

To all whom it may concern:

Be it known that I, HOWARD C. McDONALD, a citizen of the United States, residing at Buffalo, in the county of Erie and State of New York, have invented a new, original, and ornamental Design for Hanging Toilet-Racks, of which the following is a specification.

The accompanying drawing illustrates, by a perspective view, a toilet rack embodying the design.

The characteristic features of this design consist in the relatively shallow ornamental

rack body having substantially circular top and bottom walls A and B between which are provided relatively deep, separated peripheral recesses C, said body being provided at its lower peripheral portion with ornamental projections, as D.

I claim:

The ornamental design for a hanging toilet rack, as shown and described.

HOWARD C. McDONALD.
